CLAIM

The ornamental design for a brick with logo, as shown and described.

DESCRIPTION

FIG. 1 is a bottom view of a brick incorporating my new design;

FIG. 2 is top view thereof;

FIG. 3 is right side view thereof, which is identical to a left side view;

FIG. 4 is a back side view thereof, which is identical to a front side view;

FIG. 5 is a perspective view thereof;

FIG. 6 is a bottom view of a brick incorporating my new design according to a second embodiment;

FIG. 7 is a top view thereof;

FIG. 8 is a right side view thereof, which is identical to left, front and back side views;

FIG. 9 is a perspective view thereof;

FIG. 10 is a bottom view of a brick incorporating my new design according to a third embodiment;

FIG. 11 is a top view thereof;

FIG. 12 is a right side view thereof, which is identical to left, front and back side views; and,

FIG. 13 is a perspective view thereof.
